UNITED STATES PATENT OFFICE.

THEODOR KLÖTZLI, OF THOUANE, SWITZERLAND.

CONTROLLING MEANS FOR ELECTRIC HEATERS.

Application filed September 13, 1920. Serial No. 410,065.

To all whom it may concern:

Be it known that I, THEODOR KLÖTZLI, a citizen of the Swiss Confederation, and residing at Thoune, Switzerland, have invented 5 certain new and useful Improvements in Controlling Means for Electric Heaters.

My invention relates to electric irons and the like, and has for its object to provide an improved safety device for preventing 10 the same from becoming overheated.

According to my invention, an electric iron or the like is provided with a switch having a member that tends automatically to open the circuit, and is held in its circuit-closing position by a locking member which is situated in operative relation to an expansion member to be mounted on the iron or the like, so that when the expansion member expands a predetermined amount 15 owing to a rise in temperature of the iron or the like the said member moves out of its circuit-closing position and opens the circuit.

The invention consists in the construction, 25 arrangement and combination of parts described hereinafter and pointed out in the claims.

One illustrative embodiment of the invention and several modifications thereof are 30 represented by way of example in the accompanying drawing, wherein:

Figure 1 is a cross-sectional elevation of one form of safety device according to the invention, and

Figure 2 is a vertical longitudinal section taken on the line II—II in Figure 1;

Figure 3 is a view corresponding to Figure 1 showing a second form, and

Figure 4 is a side elevation of an iron 40 comprising a modified detail;

Figure 5 is a vertical sectional elevation showing a third form;

Figure 6 is a section taken on the line VI—VI in Figure 5, and

Figure 7 is a bottom plan view thereof.

In the construction shown in Figures 1 and 2, the body 1 of an electric iron carries at its rear end two contact pins 2 which are received by the two contact sockets 3 and 4 provided in the plug 5. The socket 3 is connected by a wire 6 and a terminal 7 with a wire 8 of a plug flexible-cord connected to the latter, whilst the other wire 9 of the same cord can be brought into electrical connection 55 with the socket 4 by two laterally-bent

contact-springs 12 and 13 mounted respectively on arms 10 and 11 projecting laterally away from the body of the plug 5.

The leaf spring 13 tends to move away from the contact spring 12 to break the circuit; in order to close the circuit it must therefore be pressed against the spring 12. For this purpose there is provided a slide 15 having a lateral pin 14 of insulating material. This slide is movable up and down, 60 is guided by two pins 16 mounted on a sheet-metal casing 17 detachably attached to the plug 5, and is normally held in its upper position by a spiral spring 18. By pressing a knob 19 on the top of the slide 15 the latter can be moved against the action of the spring 18 into its lower position, wherein it is held by a catch 20 arranged to engage in a recess 21 in the slide.

The catch 20 has below its pivot 22 a short 75 arm 23 which carries a micrometer screw 25 arranged to coat with the free end of a rod or bar 24 of angular section having its other end firmly connected with the body 1 of the iron.

This bar 24 consists of a metal, for example zinc, having a considerably greater coefficient of expansion than that of the body of the iron, and lies lengthwise freely on the latter, being thus in heat-conducting relationship therewith. If the iron has 80 attained a certain temperature which, if it lasted a long time, might lead to the destruction of, for example, the heating resistance, then in consequence of the expansion in

length of the bar 24 the catch 20 will be disengaged by the bar from the recess 21 in the slide 15. This slide will at once fly upwards, its pin 14 will consequently release the contact spring 13 which will immediately move away from the contact spring 12 and thereby break the circuit. This interruption will be permanent, that is to say the current will not be switched on automatically when the temperature of the iron falls 90 again; the circuit must be closed manually by pressing down the slide 15. Also, the circuit cannot be kept closed by the device before the bar 24 has contracted owing to the iron cooling.

In the example described above with reference to Figures 1 and 2 the switch (15) together with the plug (5) is detachably mounted on the iron. Alternatively, the entire device can be fixedly mounted on the 100 105 110

iron and so constructed that an ordinary plug can be connected to it. For this purpose, as shown in Figure 3, the socket 3' is tubular and has its upper end arranged 5 to receive the pin of a plug; above the socket 4' is arranged a sleeve 125 for receiving the other pin of the plug, which sleeve 125 carries the arm 11. The lower part of the sleeve 3' and the socket 4' are pushed onto 10 pins on the iron and can be securely fixed thereto each by a set-screw, for example, not shown in the drawing.

In the examples described above the rod 24 is attached directly to the iron. The expansion in length of the latter due to its being heated acts counter to that of the rod 24. In order to obviate this drawback in the construction according to Figure 4 15 the rod 24 is fixed not directly to the body 29 of the iron itself, but to a rod 27 mounted on the casing of the switch, a layer of heat insulating material (not essentially shown) being provided between the two rods. The expansion of the iron can therefore in no 25 way materially impair the effect of the expansion of the rod 24, because the rod 27 will experience a scarcely appreciable expansion due solely to heat radiated by the iron.

30 In the embodiments illustrated in Figures 1 to 4 the expansion member is in the form of a relatively long rod that has to be arranged outside the casing of the switch on the iron. This gives, to the device a clumsy 35 appearance, and necessitates the switch and the rod being suitably arranged on the iron. A construction in which the expansion member is accommodated within the switch casing would therefore be preferable in practice. In the embodiment according to Figures 40 5 to 7 this end is attained by making the expansion member of at least two rods arranged side by side which act longitudinally one on the other at one end by means of 45 an intermediate member.

Referring to Figures 5 to 7, the plug 35 of insulating material is provided with two contact sockets 33 and 34, at the usual distance apart whereof the latter has on a 50 laterally projecting lug 40 an upwardly extending contact leaf spring 43. A contact lug 41 of a connection member 39 arranged above the socket 34 projects out of the plug 35 adjacent to, but spaced apart from the upper end of this spring 43. The wires of a flexible cord from a plug can be led to the contact socket 33 and to the member 39 by way of a hole 38 that is made in the top 55 of the plug 35 and has two branches at its lower end. In order to close the switch 41, 43 or the circuit terminating thereat, a cut-out member, in the form of a metal ring 44 can be inserted from above between the two members 41, 43 by pressing down- 60 wards against the action of the spring 48

a sliding rod 45 that is guided to move up and down at a side wall of the casing 47 and carries the ring 44, but is insulated therefrom. When the rod 45 is in its lowest position it is held therein by a spring-controlled catch 50 that takes into a recess 51 in the rod. This catch 50 has below its pivot 52 a short arm 53 which extends into operative relation with a rod 54 of material, for example zinc, having a high coefficient 75 of expansion. This rod 54 is guided to slide longitudinally on the bottom of the switch casing 47 in a recess in the plug 35 close to a second rod 54' that consists of the same material as the rod 54. A sickle-shaped 80 rolling lever 57 resting freely in the recess 49 on the bottom of the casing 47 is provided at the ends of the rods 54, 54' remote from the catch 50 and serves to impart to the rod 54 the longitudinal expansion of the 85 rod 54' due to its rise in temperature. In order that the heat can be transmitted directly from an iron provided with the safety device to the rods 54, 54' which conjointly 90 constitute the expansion member, the bottom of the casing 47 has in it a slot 47', through which lugs or projections 56 on the bottom faces of the rods can extend and bear directly upon the iron when the plug 35 is pushed home on the pins provided for it on the iron. A set-screw 55 is screwed into the rod 54' in the side wall of the casing 47 that carries the thrust rod 45, which screw serves to predetermine at 95 what temperature the electric current is to be cut off or the switch is to be opened. When the expansion member has expanded an amount corresponding to the maximum admissible temperature, the catch 50 will release the thrust rod 45 which will at once 100 fly into its upper end position. The contact ring 44 thereby breaks contact with the spring 43 and consequently breaks the circuit. When the iron or the expansion member cools the circuit is not closed automatically, but its closure must be effected manually by depressing the rod 45. 110

By subdividing the expansion member 54, 54' into two or more parts it is possible to accommodate it in a small space such as 115 inside the casing of the switch. The safety device in the form last described with reference to Figures 5 to 7 can consequently be put on the market as a unitary structure, and can be readily connected to a 120 flexible cord of a plug in the ordinary manner. Also the appearance of an iron is not impaired by the device.

The described safety device can be applied to most existing electric irons and also, for 125 example, to electric cooking utensils, and has the advantage that its employment prevents not only overheating of the iron or the like, but also consequential scorching of linen and other combustible articles in 130

contact with the hot iron or the like, and consists in a metal rod having a high coefficient of expansion, means being provided projecting from the bottom of the said casing 25 and arranged to transmit heat to the said

I claim:

5. 1. A thermostatic switch comprising a detachable casing, electric contacts therein, an expansion member, a movable member for opening and closing the said contacts, a means tending to move the said movable member to its inoperative contact-opening position, and a catch pivoted in said casing for holding the said movable member in its operative contact closing position against the action of the said means, the said catch being so disposed relative to the said expansion member that on the latter being expanded by heat a predetermined amount, the said catch is automatically withdrawn so as to release the said movable member 20 from its operative contact-closing position.
15. 2. A thermostatic switch as specified in claim 1, in which the said expansion member
3. A thermostatic switch as specified in claim 1, in which the said expansion member consists in a metal rod having a high coefficient of expansion, means being provided projecting from the bottom of the said casing and arranged to transmit heat to the said rod, the latter consisting of two adjacent parts and a sickle-shaped rolling lever 30 at the ends of the said parts for imparting the expanding movement of the one part to the other.

In testimony whereof, I affix my signature in the presence of two witnesses.

THEODOR KLÖTZLI.
